UNITED STATES PATENT OFFICE.

WILLIAM H. SCOTT, OF MAPLEWOOD, MISSOURI, ASSIGNOR TO DONALD R. NIEDERLANDER,
OF ST. LOUIS, MISSOURI.

COMBINED BOLSTER AND DRAFT-RIGGING.

No. 910,151.

Specification of Letters Patent.

Patented Jan. 19, 1909.

Application filed February 11, 1907. Serial No. 356,753.

To all whom it may concern:

Be it known that I, WILLIAM H. SCOTT, a citizen of the United States of America, residing in Maplewood, in the county of St. Louis and State of Missouri, have invented certain new and useful Improvements in a Combined Bolster and Draft-Rigging, of which the following is a full, clear, and exact description, reference being had to the accompanying drawings, forming part of this specification.

My invention relates to a combined bolster and draft rigging in which the bolster is provided with a separable member in order that the draft rigging may be readily introduced and removed therefrom without disturbing any other part of the car with which the appliances are associated and also in which the draft rigging is provided with spring controlled friction members and part of which have frictional bearing against the bolster.

The principal objects of my invention are: First, to provide a construction of bolster whereby the transversely movable friction members of a draft rigging of the character named are caused to operate directly in conjunction with the bolster in order that the force exerted by said members in their transverse movement will be received directly by, and applied to, the bolster in a direction longitudinally thereof. Second, a construction whereby members of the bolster serve to receive a frictional contact of members associated with the transversely movable friction members of the rigging, thereby increasing the frictional action during the operation of the rigging.

In order that my invention may be fully understood I will proceed to describe it with reference to the accompanying drawing, in which:

Figure I is in part a top or plan view of my rigging and in part a horizontal section of the bolster. Fig. II is a longitudinal vertical section taken on line II-II, Fig. I. Fig. III is a vertical cross section taken on irregular line III-III, Fig. I. Fig. IV is a side elevation of the draw bar at the point of connection between the shank of the car coupler and the connection members fitted thereto. Fig. V is a horizontal section taken through the bolster and illustrating a modification. Fig. VI is a section taken longitudinally through the central part of the bol-

ster and transversely through the draft rigging.

1 designates the body of my bolster which, as herein shown, is of I-beam form and has the central longitudinal web 2. The bolster is provided with a transverse and extended centrally located recess 3 that is open at the lower side of the bolster and is adapted to be closed by a detachable correspondingly extended compression plate 4 which is provided at its lower side with a center bearing 5 adapted to seat upon a corresponding bearing at the upper side of the truck bolster and at its upper side with parallel slides 5'. The compression plate 4 is made detachable in order that the draft rigging to be hereinafter described may be readily inserted into the bolster and be moved therefrom.

6 designates extended webs located transversely of the bolster and which constitute the side walls of the extended central recess in the bolster. These webs preferably extend laterally beyond the sides of the bolster as shown in the drawings and their faces are preferably parallel with each other. At the rear ends of the webs are stop lugs 7 and at the forward ends of the webs are stop lugs 8.

The draw bar of the draft rigging includes the car coupler shank 9 provided at its rear end with an enlargement 10, a pair of channel shaped connecting bars 11 riveted or otherwise suitably secured together and having hook-shaped ends riveted or otherwise secured to the enlargement of the shank 9 and a loop 12 having hook-shaped ends which are riveted or otherwise suitably secured to the connecting bars. The object in so constructing the draw bar is to lengthen said bar sufficiently for it to reach the body of a railway car when applied thereto, this being accomplished by the introduction of the bars 11, which are virtually splice bars, between the coupler shank and loop of the draw bar.

13 designates a follower block that is located within the forward end of the draw bar loop.

14 designates a block that occupies a position between offset ends of the connecting bars 11 of the draw bar which are spread apart to permit the locating of said block between them, the connecting bars being bent abruptly at the forward end of the block for the purpose of affording shoulders against 110

which the block bears in order that resistance relative to the loop may be offered longitudinally of the draw bar. The fastening means that unite the ends of the draw bar 5 loop to the connecting bars 11 pass through the block 14 and consequently all of said parts are very strongly united.

15 designates a rear friction block having forwardly projecting side wings 15^a and that 10 is located within the loop of the draw bar and occupies a position between the transverse webs 6 of the bolster and has its rear face arranged in opposition to the stop lugs 7 of said webs. This friction block has a V-shaped forward end that enables the block 15 to perform an office to be hereinafter mentioned. 16 is a forward friction block that is located within the loop of the draw bar and has a V-shaped rear end that faces the 20 V-shaped forward end of the rear friction block 15. Between the forward friction block and the follower plate 13 are springs 17 that bear against said members.

18 designates a pair of transverse friction blocks which are located between the rear and forward friction blocks 15 and 16 of the draft rigging and which are provided at their front and rear ends with inclined faces that bear against the faces of the V-shaped 30 ends of said rear and forward blocks, thereby providing for the action of the V-shaped ends of the rear and forward blocks to spread the transverse friction blocks in a direction transversely of the draw bar and longitudinally of the bolster.

19 is a rod that passes transversely through the two transverse friction blocks and is surrounded by springs 20 located between the transverse friction blocks and the transverse 40 webs 6 of the bolster.

21 are side friction plates slidable on the parallel slides and adapted to travel thereon and which are loosely mounted upon the rod 19 and are interposed between the outer ends 45 of the springs 20 and the transverse webs 6 of the bolster, the said friction plates 21 being designed to ride in frictional contact with said transverse webs as will hereinafter appear.

50 In the practical use of my bolster and rigging the draw bar in moving rearwardly acts to impart a rearward movement to the follower block 13 with the result of compressing the springs 17 between said follower block and the forward friction block 16. As the spring is compressed the rearward movement of the forward friction block is resisted by the spring controlled transverse friction blocks 18. Upon the forward movement of the draw bar its loop 60 causes the rear friction block 15 to be moved forwardly and during the initial movement of these parts the transverse friction blocks, the parts carried thereby and the forward friction block move in a forward direction

with the result of causing the springs 17 to be compressed between the forward friction block and the follower block 13. When the force applied to the rigging is sufficient to compress or approximately compress the 70 springs 17 in either the rear or forward movement of the draw bar the forward or rear friction block 16 or 15, according to the direction in which the draw bar is moving, act against the transverse friction blocks 75 with the result of causing said transverse friction blocks to be spread apart under the influence of the forward and rear friction blocks. The springs bearing against said transverse friction blocks are therefore 80 acted upon, whereby they are caused to exert force against the friction plates 21 mounted loosely upon the rod 19, and said friction plates are forced firmly into bearing against the transverse webs of the bolster with the 85 result of causing a frictional action between said parts to constitute a friction brake resistance against the movement of the draw bar supplemental to the resistance offered by the springs and other frictional parts of the 90 rigging. All of the strain that is imposed upon the bolster during the thrust of the transversely moving parts of the rigging is directed longitudinally of the bolster and as the bolster can the more capably resist thrust 95 applied in such direction, the construction is an important one. This is particularly true in the use of a bolster having a web extending longitudinally thereof and against which the thrust of the transversely moving members of the rigging is directed.

In Figs. V and VI I have shown a modification in which the transverse webs 6' of the bolster are made separate from the body of the bolster and suitably secured to said 105 body, for instance, by the use of rivets. The webs in this modification correspond to the transverse webs in the construction previously described and the remainder of the bolster and the draft rigging are of the same 110 construction as that previously described.

My bolster is of such construction that it is of value in the use of any draft rigging in which transversely movable members are utilized for the reason that any force that 115 may be delivered outwardly from the transversely movable members of the rigging is directed longitudinally of the bolster and very effectually resisted, due to the direction of the thrust relative to the bolster. I am 120 aware that draft riggings of the kind named have been mounted between the draft sills or center sills of railway cars and desire to call attention in this connection to the fact that any force delivered from the transversely 125 movable members of the rigging is delivered transversely of the draft sills or center sills which are in many cases inefficient to resist the force applied to them, due to the direction in which said force is applied.

Claim:

The combination of a bolster having as integral parts thereof webs extending transversely of the bolster parallel with each other, spaced apart and projecting laterally beyond the sides of the bolster, the webs being provided at the inner faces of their end portions with opposing stop lugs; and a

draft rigging located between said webs and having followers adapted to engage said stop lugs, substantially as set forth.

WILLIAM H. SCOTT.

In presence of—

BLANCHE HOGAN,
E. S. KNIGHT.
